CLAIM

The ornamental design for a keyboard, as shown and described.

DESCRIPTION

FIG. 1 is a perspective view of a keyboard showing our new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The broken line showing of various regions in FIGS. 1, 2, 5 and 7 is for illustrative purposes only and forms no part of the claimed design.

1 Claim, 4 Drawing Sheets
